DISCHARGE ELECTRODE STRUCTURE FOR
ELECTRICAL PRECIPITATION APPARATUSFrederick W. Phillips, Toronto, Ontario, Canada,
assignor to Western Precipitation Corporation,
Los Angeles, Calif., a corporation of California

Application November 21, 1942, Serial No. 466,467

11 Claims. (Cl. 183—7)

This invention relates generally to apparatus for electrical precipitation of suspended particles from gases, and more particularly to discharge electrode structures for such electrical precipitation apparatus.

It is common practice in electrical precipitation apparatus to employ a "discharge" electrode structure including one or more discharge electrodes in the form of linearly-extended elements of relatively small diameter, or having formations of relatively small radius of curvature, well-known examples including wires, small diameter rods, twisted ribbons and twisted square bars. This discharge electrode structure, which in operation is maintained at a high uni-directional potential, is so constructed and mounted that the discharge electrode elements extend in parallel spaced relation with respect to an opposing grounded electrode structure which is of "non-discharging" character, such as an extended-surface plate, relatively large diameter pipes, or the like, and the particle-laden gas is passed between the opposing electrodes, as is well understood in the art.

In the following description and appended claims, the term "discharge electrode" will be understood to designate an electrode that facilitates corona discharge therefrom, because it has a configuration that establishes a sufficiently high potential gradient at or near its surface to create corona discharge before there is a disruptive discharge or sparkover. For this purpose, the discharge electrode usually takes the form of a member of small surface area, such as a small diameter wire or a rod provided with sharp edges or points, whereby there may be created in the immediate vicinity thereof a sufficiently high electric field intensity to cause ionization and corona discharge. The term "non-discharging electrode" will be understood to designate an electrode that minimizes or prevents corona discharge therefrom because it has a configuration that establishes a sufficiently low field concentration at or near the surface to suppress corona discharge at elevated potentials lower than the voltage required for disruptive discharge or sparkover. For this purpose, a non-discharging electrode is usually one of extended surface area, substantially free from sharp corners or other parts of sharp surface curvature at all portions which are located within the electric field, so as substantially to avoid ionization or corona discharge at that electrode.

The discharge electrode structure for precipitators of the class mentioned usually embodies

5 supporting means which supports each linearly-extended discharge electrode element at two or more positions spaced longitudinally of the element, said elements being so mounted at one of the positions as to be restrained against longitudinal movement and in good electrical contact with the supporting means, and the elements being merely confined by the supporting means against transverse movement at the other position or positions and being left free for longitudinal movement to accommodate longitudinal expansion and contraction relative to the supporting means. The support provided at the last-mentioned position or positions is not such as affords 10 a good electrical connection between the element and the supporting means.

When the precipitator is handling certain types of gases, as, for example, dry converter gases, there is some considerable unavoidable sparking 15 and arcing between the high potential discharge electrode structure and the grounded non-discharging electrode structure. This sparking or arcing may occur between any point on any of the linearly extending discharge electrode elements and a point on the opposing grounded electrode structure. Consequently, any tendency thereof to cause burning away of the discharge electrode elements is not apt to cause serious trouble because such sparks or arcs do not usually occur repeatedly at any one point on a discharge electrode element. However, when such a spark or an arc jumps the gap between the grounded non-discharging electrode structure and a point on a discharge electrode element, the potential 20 of such point on the discharge electrode element is very greatly lowered, and a heavy current flows momentarily between such point and the high potential supporting means for the element. If such point happens to be near the position of support for the element at which the element is longitudinally restrained, at which position a good electrical connection between the element and the supporting means has been provided, the heavy current flow spoken of passes through said electrical connection to the supporting means without event. But if the point of sparkover or arc 25 happens to be near a position of support for the element at which only transverse restraint has been provided, and at which good electrical connection is difficult to provide, arcing will occur between the electrode element and the supporting means at such position, due to the relatively high potential difference thus created momentarily between these parts that are normally at substantially the same potential. Such arcing between 30 35 40 45 50 55

these parts of the high potential electrode structure is inherently localized at the positions of loose engagement of the linear discharge electrode elements with the last-mentioned supporting means, and the repeated occurrence of such arcs at these positions eventually burns off the electrode elements, causing considerable inconvenience, shut-down time for replacement, and expense.

The primary object of the present invention is, accordingly, the provision of a discharge electrode structure adapted to be maintained at high potential with respect to an opposing grounded electrode structure, and embodying linearly-extended electrode elements supported at two or more points by supporting means forming parts of said discharge electrode structure and normally maintained at substantially the same potential as the electrode elements, in which simple and effective provision is made to safeguard against burning off the extended electrode elements at their points of support on the supporting means as a result of arcing therebetween in the manner described.

Broadly stated, the present invention accomplishes this object by the provision of a high-tension discharge electrode structure including a supporting means and linearly-extended discharge electrode elements mounted thereon, in which the linearly-extended discharge electrode elements are each provided with a support at one point on said supporting means which is of such character as to provide a good electrical connection between the element and the supporting means, and with a positioning member of insulating material mounted on the supporting means which loosely engages the electrode element at a position spaced longitudinally from the first-mentioned point of support and limits transverse movement of the element but leaves it free of longitudinal restraint. Such insulation positioning members prevent arcing at all positions of support for the extended discharge electrode elements at which they are provided, causing all current flows between the electrode element and the supporting means to take place at the points of support at which the electrical connections are provided, and hence eliminate burn-off of the electrode elements at those positions.

The invention will be more fully understood by now referring to the following detailed description of several illustrative embodiments thereof, reference for this purpose being directed to the accompanying drawings, in which:

Fig. 1 is an elevation of a high-tension discharge electrode structure embodying the invention; Fig. 2 is an enlarged detail taken from Fig. 1, with parts broken away, showing in detail the nature of the upper supporting means for the discharging electrode elements; Fig. 3 is a vertical medial section showing in detail the nature of the intermediate and lower positioning means for the discharge electrode elements of the structure of Fig. 1; Fig. 4 is a plan view of the positioning means shown in Fig. 3; Fig. 5 is a view similar to Fig. 3, but showing a modification; Fig. 6 is another view similar to Fig. 3, but showing a further modification; Fig. 7 is a somewhat diagrammatic sectional view of a multiple gas tube type of precipitator in which the improvements of the present invention have been incorporated; Fig. 7a is a detail showing an insulator of Fig. 7 in enlarged longitudinal section; Fig. 8 is a fragmentary elevation of a modified form of high-tension discharge electrode structure embodying the im-

provements of the present invention; Fig. 9 is a fragmentary elevation of another type of discharging electrode structure embodying the invention; Fig. 10 is a detail section taken on line 5 10—10 of Fig. 9; and Fig. 11 is a detail section taken on line 11—11 of Fig. 10.

Fig. 1 shows the high-tension discharge electrode structure of a typical electrical precipitator. The remainder of the precipitator may be of any 10 conventional or appropriate type; for a description of a complete precipitator of a type utilizing a discharging electrode structure of the type of Fig. 1, see Patent No. 1,846,169, granted February 23, 1932, to C. H. Weiskopf in which an entire 15 discharge electrode structure of generally similar construction is shown as maintained at high potential with respect to an opposing grounded electrode structure. Referring now more particularly to Fig. 1, the discharge electrode structure, generally designated by numeral 15, includes a suitable supporting means or framework embodying horizontally-spaced vertical frame bars 16 and horizontal, vertically-spaced upper, intermediate and lower cross-members 17, 18 and 19, respectively, inter-connecting vertical bars 16. These cross-members 17, 18 and 19, which are preferably and illustratively in the form of pipes, may be provided with any suitable form of mountings on the vertical frame bars 16. For instance, 20 intermediate and lower pipes 18 and 19 may be received in sockets 18a mounted on bars 16, and upper pipe 17 may be supported at each end by a pin 17a extending upwardly from the upper flange of a horizontal channel member 17b 25 mounted on the adjacent frame bar 16, the pin 17a entering a hole 17c in the lower side of the pipe and supporting the pipe by engaging its upper side from below, as clearly illustrated in Fig. 2.

Horizontal pipes 17, 18 and 19 are provided 30 with horizontally-spaced sets of vertically-aligned openings adapted for reception of the vertical, horizontally-spaced discharging electrode elements 20. These discharging electrode elements 20 may take various forms—such as 35 wires, fine rods, twisted square bars, twisted ribbons, or other forms of linearly-extended elements of relatively small diameter or affording formations of relatively small radius of curvature. For the purpose of the present disclosure, 40 I show the elements 20 in the form of twisted square bars, as illustrated in Fig. 3. These bars are received in vertically-aligned apertures 21 formed in the upper and lower sides of upper supporting pipe 17, the apertures 21 being preferably 45 of such size as to freely receive the electrode element but to confine it comparatively closely against transverse displacement. The upper end portion of each electrode element 20 is preferably formed with a suitable head which engages the top side of pipe 17, and by which the element is suspended. In the form illustrated in 50 Figs. 1 and 2, this head is formed by the simple expedient of doubling back the upper end portion 22 of the bar, so that the end 23 engages the top side of pipe 17 in the manner clearly illustrated in Fig. 2. This engagement between the head formed 55 on the upper end of bar 20 and at the top side of supporting pipe 17 serves the dual purpose of supporting the bar against longitudinal movement in a downward direction, and providing a good electrical connection between the bar and the supporting pipe. Thus, all parts of the high tension discharge electrode structure, including 60 discharging electrode elements 20 and supporting members 18 and 19, are in electrical contact with 65 70 75

one another through the upper supporting members 17 and vertical frame members 16 and are normally maintained at substantially the same potential.

The openings 25 formed in supporting pipes 18 and 19 for passage of electrode bars 20 are of substantially increased diameter as compared with the openings 21 in the upper pipe 17, and receive insulation positioning members for the bars 20, preferably and here shown as insulator bushings or sleeves 26, of glass, ceramic, or any suitable insulation material, and preferably formed at their upper ends with shoulder means engageable with the supporting pipe to resist longitudinal displacement.

In the specific form illustrated in Fig. 3, this shoulder means is provided by flaring the upper end portion of the bushing outwardly, as indicated at 28. If the bushing is composed of glass, this may easily be accomplished by heating the upper end portion of the bushing and flaring it while it is hot. The flared portion 28 then serves as the shoulder, and supports the bushing as indicated in Fig. 3. The internal bore 29 of the bushing is of such diameter as will freely or loosely receive the twisted bar 20, or other linearly-extended electrode element, so as to confine the bar against transverse displacement, without restraining it longitudinally. Preferably, the bore in the bushing is of at least slightly larger diameter than the maximum thickness dimension of the electrode element, so as to avoid any possibility of frictional bind between said element and the bushing. The bushing extends well above and below the pipe 18 to prevent sparkover between the electrode element and the pipe.

Fig. 5 shows a modified insulator bushing 26a, formed at the top with an enlarged head 30 presenting a downwardly-facing annular shoulder 31 which is engageable with the top of pipe 18. As a further modification, the bore 29a of the bushing of Fig. 5 is shown to diverge in a downward direction from a point preferably a short distance below its upper end, as illustrated. This downwardly diverging bore permits foreign objects that might become lodged between the electrode bar 20 and the bushing to work free and fall from the bushing somewhat more readily than would otherwise be the case. However, this form of bushing may, if desired, be made with a cylindrical bore. In either case, bushings of this form may be made by a moulding or other forming operation, using either ceramic or vitreous insulating materials.

Fig. 6 shows an insulator bushing 26b formed at the top with an enlarged head 34 affording a downwardly-facing annular shoulder 35, the bushing in this instance being received within and supported by a metal sleeve 36, which is in turn received by the openings 25 of the pipe. As shown, the upper end of the sleeve has an outwardly-extending annular flange 37 engaging and supporting bushing shoulder 35, and the underside of said flange provides a shoulder supported by the pipe. This sleeve 36, the lower end of which terminates substantially short of the lower end of the bushing, so as to prevent sparking between the electrode bar and the sleeve, affords added support and protection for the bushing.

The described insulator bushings placed between the discharging electrode elements 20 and the supporting pipes 18 and 19 prevent arc-over between said elements and supporting pipes, and, in the event of sparkover or arcing between the

discharging electrode elements 20 and the opposed non-discharging electrode (not illustrated), all current flow between the elements 20 and the high-tension supporting structure 15 is confined to the points of engagement between the heads of the elements and the supporting pipe 17, at which the elements 20 have good electrical connections with the framework 15. The bushings thus serve as longitudinal guides for the extended electrode elements 20, confining them against transverse displacement while permitting longitudinal movement owing to longitudinal expansion or contraction, and at the same time prevent destructive arc-over between the said electrode elements and the supporting members 18 and 19 through which they are extended.

Figs. 7 and 7a show the application of the invention to a multiple-tube type of precipitator employing one or more linearly-extended discharge electrode elements in the form of flexible wires. In Fig. 7, which is largely diagrammatic, numeral 40 designates generally a fragmentarily-indicated gas supply header, understood to be supplied with gas by way of any suitable inlet means, not shown; numeral 41 designates a plurality of vertical gas tubes leading upwardly and receiving gas from header 40 and constituting collecting electrodes; and numeral 42 designates a fragmentarily indicated gas discharge header into which the gas rising in tubes 41 is discharged. Mounted within header 42, on insulators indicated at 43, is a horizontal support 44 for the high-tension discharge electrode elements which extend downwardly co-axially through collecting electrode tubes 41. These high-tension discharge electrode elements, as here shown, include a pair of relatively heavy hanger elements 45, typically in the form of twisted square bars, of the same type, for instance, as the twisted bar 20 shown in Fig. 3, and one or more flexible wires 46. Elements 45 may be supported from pipe 44 by means of suitable heads at their upper ends, which may be formed by turning back the upper end portions of the elements, as indicated at 47. The lower end portions of elements 45 pass through opposite ends of a horizontal support 48, typically in the form of a pipe, and support said pipe within header 40 through nuts 49 screwed on their lower ends. Flexible electrode wires 46, hung from pipe 44 in any suitable manner, extend downwardly from the lower ends of tubes 41 through insulator bushings 52 mounted in pipe 48 (Fig. 7a), the insulator bushings 52 being, for example, of the same type as the bushing 26 of Fig. 3, though they may be somewhat smaller in diameter. Electrode wires 46 are held taut by means of weights 53 at their lower ends. As will be evident, the insulator bushings 52 confine electrode wires 46 against transverse displacement without interfering with relative longitudinal movement between the wires and the bushings, while at the same time the bushings serve to prevent arc-over between the wires and the pipe 48.

Fig. 8 shows a modified form of high-tension discharge electrode structure, which is in general respects of the same type as that shown in Fig. 1, with the exception that the linearly-extended discharge electrode elements are secured at their lower ends to the lower horizontal frame member, rather than being hung from the upper horizontal frame member as in Fig. 1. The high-tension discharge electrode structure includes a frame, fragmentarily designated at 60 in Fig. 8, and understood to comprise one or more vertical

frame bars 61, and inter-connecting upper, intermediate and lower supporting members 62, 63 and 64, respectively, preferably and here indicated in the form of pipes. The linearly-extended discharge electrode elements 65, which are in this instance of sufficient stiffness to be supported from their lower ends, may again be typically in the form of twisted square bars, like the bars 20 of Figs. 1 and 3. The lower ends of the bars have heads 66 which engage the under side of pipe 64, and nuts 67 threaded onto the bars near the heads 66 are set against the top side of the pipe 64 to secure the bars against longitudinal displacement. The bars pass through and are guided by insulator bushings 68 set into pipes 62 and 63, the bushings 68 and the manner of their mounting being illustratively the same as is shown in Fig. 3.

Figs. 9 through 11 show another application of the invention, the linearly-extended discharge electrode elements in this instance being horizontally disposed. The high-tension supporting frame 70 includes a vertical central frame member 71 of channel section, having flanges 72, and outside vertical frame members 73, typically in the form of pipes, which are joined with member 71 by means of connecting members 74. The linearly-extended electrode elements 75 are again illustratively in the form of twisted square bars, and will be understood to pass horizontally through suitable openings in the flanges 72 of member 71 and in the vertical supporting pipes 73, the ends of the bars having heads 76 engageable with the flanges 72, and nuts 77 screw-threaded on the bars and set up against said flanges cooperating with heads 76 to support the bars against longitudinal displacement, as well as providing the necessary electrical connection between the bars and the central frame member 71. The outer end portions of bars 75 pass freely through insulator bushings 78 supported in relatively large openings 80 in vertical members 73. In the particular example shown in the drawings, the bushings 78 have flared end portions 83 at each end, and the openings 80 are preferably of such diameter as will just receive these flared end portions as the bushings are inserted. The bushings being inserted, their smaller diameter central portions 84, which are of lengths substantially equal to the diameter of the pipes 73, rest at the bottoms of openings 80, and the flared end portions of the bushings then serve to restrain the bushings against longitudinal displacement with respect to the pipes 73.

In summary, in all of the disclosed forms of the invention, each linearly-extended discharge electrode element is provided with a support on the discharge electrode supporting frame which confines it against longitudinal displacement and which also provides a good electrical connection between the element and the frame, and with at least one insulation support or guide on said frame which confines it against transverse displacement without restricting its free longitudinal movement. This insulation support or guide prevents current flow between the electrode element and the frame except at the point of support where the element is longitudinally restrained; at which point a sufficiently good electrical connection is provided to prevent destructive arcing; and thus eliminates the burning off of the electrode elements at their longitudinally-unrestrained points of support.

It will be understood that the drawings and description are merely illustrative of and not

restrictive on the invention, and that various changes in design, structure and arrangement may be made without departing from the spirit and scope of the invention or of the appended claims.

5. I claim:

1. In a discharge electrode structure for an electrical precipitator, the combination comprising: a linearly-extended discharge electrode member; an electrode positioning member formed of insulating material; and electrically connected conductive frame members including a member supporting said electrode member at one position and electrically connected thereto and a member supporting said positioning member in loose engagement with said electrode member at a position longitudinally removed from said one position in such a manner as to limit transverse movement of said electrode member and permit longitudinal movement thereof relative to said positioning member.

2. In a discharge electrode structure for an electrical precipitator, the combination as set forth in claim 1, said positioning member being formed as a sleeve surrounding said electrode member.

3. In a discharge electrode structure for an electrical precipitator, the combination comprising: a linearly extended discharge electrode member; a positioning member formed of insulating material loosely engaging said electrode member in such manner as to limit transverse movement thereof and permit longitudinal movement thereof relative to said positioning member; and electrically connected conductive frame members including a member supporting said electrode member at one position and electrically connected thereto and a member supporting said positioning member in engagement with said electrode member at a position longitudinally removed from said one position, said positioning member electrically insulating said electrode member from said last named supporting member.

4. In a discharge electrode structure for an electrical precipitator, the combination set forth in claim 3, said positioning member being formed as a sleeve surrounding said electrode member.

5. In a discharge electrode structure for an electrical precipitator, the combination as set forth in claim 3, said positioning member being formed as a sleeve surrounding said electrode member and projecting longitudinally at both ends beyond said last-named supporting means.

6. In a discharge electrode structure for an electrical precipitator, the combination as set forth in claim 3, said last-named supporting means comprising a supporting member extending transversely with respect to said electrode member and having an opening through which said electrode member extends, and said positioning member being formed as a sleeve extending through said opening, surrounding said electrode member, and provided with shoulder means engaging said last-mentioned supporting member to resist longitudinal movement of said sleeve.

7. In a discharge electrode structure for an electrical precipitator, the combination comprising: a vertically-extending discharge electrode member; a positioning member formed of insulating material loosely engaging said electrode member in such manner as to limit transverse movement thereof and permit longitudinal movement thereof relative to said positioning mem-

ber; and electrically connected conductive frame members including a member supporting said electrode member at one position and electrically connected thereto and a horizontally-extending supporting member supporting said positioning member in engagement with said electrode member at a position vertically removed from said one position, said last-named supporting member having an opening through which said electrode member extends, and said positioning member being formed as a sleeve extending through said opening, surrounding said electrode member, and provided with shoulder means engaging said supporting member to support said sleeve thereon.

8. A discharge electrode structure for an electrical precipitator comprising a supporting frame formed of electrically conducting material and including at least two electrically connected frame members extending substantially parallel to and spaced from each other; a linearly-extended discharge electrode member engaging and supported by and in electrical contact with one of said frame members; and a positioning member formed of insulating material mounted on and supported by the other frame member, and loosely engaging said electrode member in such manner as to limit transverse movement thereof and permit longitudinal movement thereof relative to said positioning member, and electrically insulating said electrode member from said other frame member.

9. A discharge electrode structure for an electrical precipitator as set forth in claim 8, wherein the positioning member is formed as a sleeve surrounding the electrode member.
- 5 10. In a discharge electrode structure for an electrical precipitator, the combination comprising: a linearly-extended discharge electrode member; a positioning member formed of insulating material loosely engaging said electrode member in such manner as to limit transverse movement thereof and permit longitudinal movement thereof relative to said positioning member; and electrically connected conductive frame members including a member supporting said electrode member at one position against both longitudinal and transverse displacements and electrically connected thereto and a member supporting said positioning member in engagement with said electrode member at a position longitudinally removed from said one position, said positioning member electrically insulating said electrode member from the last-named supporting member.
- 15 20 25 30 11. A discharge electrode structure for an electrical precipitator as set forth in claim 10, wherein the positioning member is formed as a sleeve surrounding the electrode member.

FREDERICK W. PHILLIPS.
